[57] CLAIM

The ornamental design for a dental amalgam condenser tip or the like, substantially as shown and described.

DESCRIPTION

FIG. 1 is a top plan view of a dental amalgam condenser tip or the like showing my new design;

FIG. 2 is a bottom plan view of said dental amalgam condenser tip or the like;

FIG. 3 is an elevational view of the right side of said dental amalgam condenser tip or the like;

FIG. 4 is an elevational view of the left side of said dental amalgam condenser tip or the like;

FIG. 5 is an elevational view of the front of said dental amalgam condenser tip or the like; and

FIG. 6 is an elevational view of the rear of said dental amalgam condenser tip or the like.

The broken lines are shown for illustrative purposes only.
